US00D979509S

(12) **United States Design Patent** (10) **Patent No.:** **US D979,509 S**
(45) **Date of Patent:** **** Feb. 28, 2023**

(54) **CONNECTOR**

(71) Applicant: **SONY INTERACTIVE ENTERTAINMENT INC.**, Tokyo (JP)

(72) Inventors: **Naoki Ogishita**, San Mateo, CA (US); **So Morimoto**, Tokyo (JP)

(73) Assignee: **SONY INTERACTIVE ENTERTAINMENT INC.**, Tokyo (JP)

(**) Term: **15 Years**

(21) Appl. No.: **29/736,338**

(22) Filed: **May 29, 2020**

(51) LOC (14) Cl. **13-03**

(52) U.S. Cl.

USPC **D13/133; D13/147**

(58) **Field of Classification Search**

CLAIM

The ornamental design for a connector, as shown and described.

DESCRIPTION

FIG. 1 is a perspective view of front, top and left side of a first embodiment of a connector showing our new design; FIG. 2 is a front view of the first embodiment thereof; FIG. 3 is a rear view of the first embodiment thereof; FIG. 4 is a left side view of the first embodiment thereof; FIG. 5 is a right side view of the first embodiment thereof; FIG. 6 is a top view of the first embodiment thereof; FIG. 7 is a bottom view of the first embodiment thereof; FIG. 8 is a perspective view of front, top and left side of a second embodiment thereof; FIG. 9 is a front view of the second embodiment thereof; FIG. 10 is a rear view of the second embodiment thereof; FIG. 11 is a left side view of the second embodiment thereof; FIG. 12 is a right side view of the second embodiment thereof; FIG. 13 is a top view of the second embodiment thereof; and, FIG. 14 is a bottom view of the second embodiment thereof. The broken lines in the drawings illustrate features for a connector that form no part of the claimed design.

1 Claim, 8 Drawing Sheets
